(57) **CLAIM**

The ornamental design for the tail rotor yoke assembly, as shown and described.

DESCRIPTION

FIG. 1 is a perspective view of a tail rotor yoke assembly of our new design;

FIG. 2 is a plan view thereof;

FIG. 3 is a back elevation thereof;

FIG. 4 is a view thereof along line 4—4; and,

FIG. 5 is a side elevation view thereof with the opposite side being a mirror image.
